UNITED STATES PATENT OFFICE.

ENOCH GOOLNIK, OF MILE END, LONDON, ENGLAND.

APPARATUS FOR GRINDING AND SHARPENING RAZORS, KNIVES, AND THE LIKE.

1,113,210.

Specification of Letters Patent.

Patented Oct. 13, 1914.

Application filed May 7, 1914. Serial No. 836,916.

To all whom it may concern:

Be it known that I, ENOCH GOOLNIK, residing at 1° Tredegar Square, Mile End, London, England, have invented certain new and useful Improvements in Apparatus for Grinding and Sharpening Razors, Knives, and the like; and I do hereby declare the following to be a full, clear, and exact description of the invention, such as will enable others skilled in the art to which it appertains to make and use the same.

This invention relates to apparatus for grinding and sharpening razors, knives and the like and has for its object to provide a simple and efficient machine or apparatus for this purpose, whereby, the sharpening or grinding, and in the case of razors, stropping operation may be accomplished in an easy and convenient manner.

To this end the invention consists in a pair or pairs of suitable rollers spaced apart and adapted to be continuously rotated and simultaneously slid backward and forward, the razor or knife being held in a carrier device between the rollers, said carrier device being intermittently actuated in such manner that the razor or other article is caused to bear first upon one of the said rollers forming the pair and then upon the other.

The carrier device in which the razor or the like is held during treatment is adapted to always cause the razor or the like to bear against the rollers with a resilient or elastic pressure, and means are provided for easily obtaining the exact adjustment of the razor or the like with regard to the rollers.

The accompanying drawings illustrate by way of example a machine made in accordance with the invention adapted for use for grinding and stropping razors.

Figure 1 is a part sectional side elevation of the complete machine; Fig. 2 is a side elevation from the right of Fig. 1, certain parts being removed for clearness; Fig. 3 is a sectional elevation on line A—A— of Fig. 1; Fig. 4 is a part plan of Fig. 1; Figs. 5 and 6 are details showing respectively an end view of the razor holder, and the positions of the razor blade with respect to the grinding rolls; Figs. 7 and 8 are respectively front elevation and side elevation of a modification, and, Figs. 9 and 10 are details of further modifications.

Referring first to Figs. 1-6. As shown,

the apparatus comprises a framing consisting of two spaced plates *a* *a*¹ connected by distance bolts *a*² and mounted upon a suitable base *a*⁰. Slidably and rotatably mounted in these two plates are a pair of horizontal rods *c* *c*¹ arranged parallel to each other the ends of which rods are provided with rollers *d* *d*¹ and *e* *e*¹ respectively, those *d* *d*¹ having a leather covered surface for the purpose of stropping, while those *e* *e*¹ may be composed of any suitable grinding media, such as emery, carborundum or the like.

The rods *c* *c*¹ are coupled together by gear wheels *f* *f*¹, one of which meshes with a gear wheel *f*² adapted to be driven to rotate both *f* and *f*¹ in opposite directions, from the hand wheel *g* through shaft *g*¹ and interposed gear wheels *f*³ *f*⁴ and *f*⁵.

The pairs of rollers *d*, *e*, in addition to being rotated as described, are also caused to be simultaneously slid to and fro axially. For this purpose a lever *h* is pivotally mounted to one side of the machine at *h*¹ the upper forked end of which engages with a cross bar *c*⁰ carried by the rods *c* *c*¹ and the lower forked ends of said lever *h* engage with pins *i* mounted upon a cross-head *i*¹ which is freely mounted by a pin and slot connection *i*² upon the end of a pivoted radius rod *j*. At the lower side of this rod is provided a pin or friction roller *j*¹ adapted to coact with a cam groove *k*¹ formed in a drum *k*, which cam groove is so formed as to impart a to and fro movement to the pin *j* when rotated by the handwheel *g*.

The rods *c* *c*¹ carrying the stropping and grinding rollers are formed with feathers *c*² to allow of the combined rotary and sliding movement thereof.

The razors or other implements to be operated upon are carried in holding devices shown at *X* at each side of the machine as in Fig. 1, and in side view and plan in Figs. 5 and 4. Each of these holding devices comprises a member *l* having a slot or recess *l*¹ with clamping screws *l*² and said member is hinged horizontally at *l*³ to a member *l*⁴ carried by an adjusting screw *m* from a bar *n*. The member *l*⁴ is also provided with guide rods *m*¹ adapted to slide vertically through the bar *n*. The part *l*² is pressed on each side by flat springs *m*² carried by the part *l*⁴ to maintain same normally in alinement with each other.

The bars n are hingedly mounted about a vertical pivot n^1 at each end of a rock shaft p disposed centrally above the rods $c c^1$ and said bars are adjustable about said pivots by means of a screw o one end of which is revolubly mounted in a pivoted bush o^1 on a bracket or arm p^1 while the other end of said screw works in a pivoted nut o^2 on the bar n .

10 q indicates in dotted lines the razor in position for operation the edge of which it will be noticed is just above the centers of the rollers $d e$ and by means of the adjusting screws m and o the position of the razor 15 or other implement both as regards height and alinement can be easily and exactly obtained.

The shaft p is adapted to be rocked intermittently so as to move the razor or knife 20 at the end of each sliding movement of the rollers, $d e$, from engagement with one roller of the pair to the other; this is shown in Fig. 6 where the full line q^1 indicates the position of the razor while the rollers are 25 sliding axially in one direction, and the dotted line q^2 when moving in the opposite direction.

The rocking movement imparted by the shaft p to the part l^4 is greater than that of 30 the actual movement of the razor or knife blade and thus by reason of the springs m^2 said blade is kept in contact with the respective rollers by a yielding or resilient pressure.

35 The shaft p is intermittently rocked by means of a cam r mounted on the driving shaft g^1 of the apparatus, spring pressed lever s with friction roller s^1 , link s^2 and arm s^3 . The cam r is formed with two concentric portions of different radius whereby the rock shaft p and carriers X are held stationary in one position or the other during the sliding movement of the stropping and grinding rollers.

45 In use the razors to be ground or stropped are clamped in the holders, adjusted if required in regard to the rollers and the handle turned smartly whereupon the rollers are rotated and slid along each side edge 50 alternately which combined action together with the resilient pressure quickly and efficiently effects the desired end.

The apparatus, of course, may, instead of being driven by hand, be operated from a 55 suitable motor or in other desired way.

It will be understood that any other suitable mechanism for obtaining the different motions may be employed instead of that described. For instance, Figs. 7 and 8 show 60 a modified method of imparting the intermittent side movement to the holders. In the construction the bar p is not rocked as in the previous construction but is adapted to be slid first to one side and then to the 65 other by means of a pivoted lever t having

a slotted or forked end t^1 for engaging the shaft p while the lower end is actuated by the cam r similarly to the first described arrangement. In order to insure the bar p being maintained in proper axial position 70 during its movement, a pair of toothed racks u are fixedly mounted upon the said bar adapted to co-act with a pair of pinions u^1 carried upon a counter shaft u^2 revolubly mounted in the frames $a a^1$ whereby the 75 transverse travel of the bar p is uniform. The bar p is provided with guide blocks p^1 sliding in slots or guideways p^2 in the frames which allows of the sliding movement and prevents the bar from turning. 80

Fig. 9 shows a modification of the first described arrangement for imparting the rocking movement to the bar p . In this form the intermediate levers $s s^1$ are dispensed with and a disk v having a cam groove v^1 85 formed in its face is adapted to intermittently actuate the bar p through arm v^2 and roller v^3 direct. The said cam disk v is driven in any suitable manner as, for instance, as shown, from the gear wheel f^1 by 90 wheel v^4 .

Fig. 10 shows a modified method of imparting the sliding movement to the rods $c c^1$. In this form the cam r is dispensed with and the lower end of the lever h is coupled 95 by an arm w to an extension x mounted upon a shaft y and driven through bevel gearing z .

By a further modification of the last construction the rods $c c^1$ could be coupled direct 100 to a suitably driven crank by means of a connecting rod.

Having now particularly described and ascertained the nature of my said invention and in what manner the same is to be performed, I declare that what I claim is:— 105

1. In a grinding machine, the combination, with a supporting frame, and a blade holder carried by the frame; of two shafts journaled in the frame and provided with sharpening rollers, driving mechanism for revolving the said shafts in opposite directions, a cam also revolved by the said driving mechanism, a radius-rod pivoted at one end to the frame and having a projection at 110 its free end which engages with the said cam, a crosshead pivoted to the said radius-rod, and a lever pivoted to the frame and having its opposite ends operatively connected with the said shafts and with the said crosshead 115 and operating to slide the said rollers longitudinally.

2. In a grinding machine, the combination, with a pair of sharpening rollers, of a rock-shaft arranged above and between the 120 said rollers and provided with means for oscillating it, a bar pivoted to one end of the rock-shaft and provided with means for adjusting it on its pivot, a vertically adjustable block carried by the said bar, and a clamp- 125 130

ing device for a blade pivoted to the said block and provided with springs which normally hold it in a central position.

3. In a grinding machine, the combination, with a pair of sharpening rollers, of a rock-shaft arranged above and between the said rollers and provided with means for oscillating it, a bar pivoted to one end of the rock-shaft, an arm projecting from the rock-shaft and arranged at one side of the said bar, an adjusting screw between the said arm and pivoted bar, a vertically adjustable block carried by the said bar, and a clamping device for a blade pivoted to the said block and provided with springs which normally hold it in a central position.

4. In a grinding machine, the combination, with a pair of sharpening rollers, of a

rock-shaft arranged above and between the said rollers and provided with means for oscillating it, a bar pivoted to one end of the rock-shaft and provided with means for adjusting it on its pivot, a vertically adjustable block carried by the said arm and provided with guides, a screw for sliding the said block vertically, and a clamping device for a blade provided with a horizontal pivot which connects it to the lower part of the said block and having springs which normally hold it in a central position.

In testimony whereof I affix my signature, in presence of two witnesses.

ENOCH GOOLNIK.
